WILLIAM CYRUS BRIGGS, OF WINSTON SALEM, NORTH CAROLINA, ASSIGNOR TO THE NATIONAL STAMP VENDING MACHINE COMPANY, INCORPORATED, OF FAYETTEVILLE, NORTH CAROLINA.

VENDING-MACHINE.

No. 918,416.

Specification of Letters Patent.

Patented April 13, 1909.

Original application filed February 6, 1907, Serial No. 356,101. Divided and this application filed March 14, 1908.
Serial No. 421,183.

To all whom it may concern:

Be it known that I, WILLIAM CYRUS BRIGGS, residing at Winston Salem, in the county of Forsyth and State of North Carolina, have 5 invented certain new and useful Improvements in Vending-Machines, of which the following is a specification.

My invention relates to certain new and useful improvements in vending machines of 10 the coin operated type, and in its generic nature my invention comprises a vending machine of a very simple and effective construction which can be easily and cheaply manufactured and which will readily and effectively serve its intended purposes.

My invention has for its object to provide a machine of the coin operated type which can be used for vending small articles, such as postage stamps, railway tickets and the 20 like, and in its generic nature, the invention comprises a ribbon-like envelop or holder for containing the articles to be vended, a feeding mechanism for said envelop, means for cutting the continuous envelop in sections, 25 together with an improved feeding roller guard.

This invention is a division of my co-pending application filed February 6, 1907, Serial No. 356,101, in which application the specific 30 claims are drawn to the coin operated mechanism, while in this application I make no claim to the coin controlling mechanism, *per se*, but in this application only the vending machine structure is claimed.

Other details of construction, combination and arrangement of parts will be hereinafter 35 fully described, and specifically pointed out in the appended claims, and illustrated in the accompanying drawings, in which:—

Figure 1, is a perspective view of the invention. Fig. 2, is a perspective view of the invention, the casing being removed. Fig. 3, is a rear elevation of the parts shown in Fig. 2, the parts being in the position they assume 45 just after the coin has been ejected and the feeding and cutting mechanism unlocked. Fig. 4, is a cross section on the line 4—4 of Fig. 3. Fig. 5, is a detail perspective view of the cam disk and lock carrying shaft. Fig. 50 6, is a similar view of the feed drum and its shaft. Fig. 7, is a detail section on the line 7—7 of Fig. 4. Fig. 8, is a detail perspective view of the knife guard. Fig. 9, is a similar

view of the fixed knife blade. Fig. 10, is a detail view hereinafter referred to. Fig. 11, 55 is a detail cross section of a part of my invention.

Referring now to the accompanying drawings in which like letters and numerals of reference indicate like parts in all of the figures, 60 1 designates the casing having the removable front 1^a and within which the operating mechanism of my invention is adapted to be contained.

The casing 1 has a discharge mouth 1^m, indicated in Fig. 1, and an aperture 1^s, forming the coin slot, while the glazed opening 1^p of the casing serves to expose the registering mechanism, hereinafter again referred to.

3 designates the operating knob which is 70 held to the front wall of the casing to be removable therewith, by having its hub 3^a keyed or pinned to the spindle 4^a of a shaft receiving hub 4^b rotatable in a bearing aperture in the casing front and the hub 4^b has a 75 squared bore 4^c, for a purpose hereinafter fully explained.

Within the casing is the removable frame 5, which supports the operating mechanism 80 of my machine, and this frame 5 and its carried parts are shown in perspective in Fig. 2 of the drawings. The frame 5 includes a base 5^a, a main vertical web 5^b and a secondary web 5^c, all being shaped to snugly fit within the casing. 85

Mounted in suitable apertures 5^d in the webs 5^b and 5^c is a drum shaft 6 which carries the feed drum 7 that rotates with the shaft between the webs 5^b and 5^c, and which has a series of circumferential lugs or pins 6^a, 90 suitably spaced apart, to coöperate with the apertures 100^a of the back strip 100 and exert a positive grip thereon. A guard 8 having a slot 8^a to permit passage of the pins 6^a co-95 operates with the drum 7 to hold the strip 100 against the same. The guard 8 is secured to the cross bolt 8^b, at its upper end and at its lower end is held between a plate 5^e projected from the web 5^c toward the web 5^b, and the fixed blade 50 by screws 50^a, as 100 shown. The bolt 8^b lies directly above the cam shaft 12, but spaced therefrom to permit passage of the strip 100.

Directly above the knife blade 50 is a knife guard 9 slotted at 9^a to permit passage 105 of the pin 6^a and provided with projecting

scraper feet 9^b to engage the drum 7 and pass the strip 100 from the drum between the feet 9^b and the blade 50. The guard 9 is secured to the web 5^c by screws 9^c. The off-
5 take chute 10 and its side plate 10^a are secured to the web 5^c in any approved manner. A spindle 11 projects from the web 5^c to receive the strip roll 100, which roll is loosely held in place by a disk 11^a, and collar 11^b.
10 The cam shaft 12 is mounted in bearing apertures in the webs 5^c and 5^b, and at its forward end is squared as at 12^a to fit within the bore 4^x of the hub 4^a, while a ratchet 13 turns with the shaft 12 and coöperates with
15 the pawl 13^a, spring pressed as at 14 to its engagement with the ratchet. At its rear end a cam 14^x is secured to the shaft 12 while a locking disk 15 and a mutilated pinion 16 is secured to the shaft 12 between the cam 14^x
20 and the web 5^c. The cam 14^x has a cam groove 14^a while the locking disk has an elongated recess 15^a the purpose of which will be hereinafter fully explained.

The mutilated pinion 16 has a tooth portion 16^a and a smooth surface portion 16^b to coöperate respectively with the tooth portions 17^a and smooth curved surface portions 17^b on the periphery of a master gear 17 secured to the drum shaft 6.

30 19 designates a bearing member projecting from the face of the web 5^b in which a rock shaft 20 is held. The shaft 20 carries a cam lever 21 which is secured thereto by a set screw 2^a, or otherwise, and the lever 21 has a friction roller 21^b to ride in the groove 14^a of the cam 14^x, so that as the cam rotates the shaft 20 will be oscillated.

22 designates the movable knife which is secured to the shaft 20 through an aperture 40 in the web 5^b and coöperates with the fixed knife to effect a shearing action therewith and cut the strip 100 into sections, as it is fed to the knives by the drum.

The bearing member 19 is provided with a 45 slideway 19^a in which an adjustable slide 23 is adjustably held by screws 23^a that pass through slots 23^b in the slide, the upper edge of the slide 23 serving to coöperate with the pawl 24^a of the coin pusher 24, the pawl 24^a having its under surface to ride on the upper 50 edge of the slide 23.

The cam 14^x has its rear face grooved as at 14^b to receive a plate 14^c that is adjustably held in place by a set screw 14^d and is provided with a projection 14^e to coöperate with the pawl 24^a of the coin pusher 24. The coin pusher 24 consists of an elongated body having slots 24^b through which securing bolts 24^c pass to secure the pusher 24 to the lugs 5^x on the rear face of the web 5^c, so that the pusher may have longitudinal movement. The pusher 24 also includes a heel 24^d which coöperates with an adjusting screw 24^e that passes through a lug 5^y projecting from the rear face of the web 5^c,

whereby the longitudinal movement of the pusher 24 in one direction may be adjusted for a purpose presently explained. The pusher 24 is held with its stop 24^d in contact with the screw 24^e by a coil spring 24^f, as shown.

24^g designates the coin engaging member of the pusher 24, which member is provided with a coin slot 24^h.

Pivottally secured by a stud 25^a to the rear face of the web 5^b is the locking and registering lever 25, which lever 25 is provided with a locking heel or pawl 25^b to coöperate with the locking disk 15, and at the other end the lever 25 is pivotally secured as 80 at 25^c to the operating rod 30^a of the registering mechanism 30, hereinafter again referred to. The lever 25 is also provided with an integrally formed coin receiving portion 25^g to coöperate with the coin engaging member 24^g of the pusher 24, and the coin engaging member 25^g is provided with a coin receiving slot 25^h in alinement with that of the member 24^h of the member 24^g.

26 designates the coin chute which is secured at its upper end to the rear face of the web 5^b, which web is provided with a coin slot 5^s to register with the coin slot 1^s in the casing front, and the coin chute 26 projects directly over the coin slots 24^h and 25^h of 95 the coin engaging members 24^g—25^g respectively thereof so that the coin as it falls down the slot 26 will enter the slots 24^h and 25^h and lock the coin receiving members 24^g and 25^g together.

100 The registering mechanism 30 to which no claim is made in my present application, is operated through the medium of the registering rod 30^a—30^a from the lever 25. A further description of the registering mechanism is thought to be unnecessary in this application.

105 From the foregoing description it will be seen that the manner in which my invention operates will be as follows: Assume the strip 110 100, with its contents for sale to be placed in position, and the ends of the strip fed to the feeding drum 7, and it is desired to make a sale, the operator then drops the coin into the coin slot which then falls down between 115 the coin engaging members 24^g—25^g, thus locking said members together. The operator then turns the knob 3 in a clockwise direction, as indicated by the arrows in Fig. 1, which causes the finger portion 14^e of the 120 cam carried member 14^e to pull the coin pusher 24 in the direction of the arrow in Fig. 3, which causes the lever 25 to be rocked to release the pawl 25^b from the locking disk 15 and permits the cam shaft to be 125 rotated. At the same time this occurs the tooth portion 16^a of the mutilated pinion 16, will engage with the toothed portion 17^a of the master gear 17 and rotate the feeding drum. As soon as the drum has rotated the 130

desired amount, the smooth portion 16^b of the periphery of the mutilated pinion 16 will engage with the smooth portion 17^b of the master gear 17 and hence the master gear 5 and feeding drum will not be further rotated. As soon as this engagement has been made the cam causes the movable cutting knife to operate the knives and cut off the projected end of the strip. Continuing 10 this rotation of the cam shaft the locking notch of the locking disk 15 will again come in alinement with the pawl portion 25^b of the lever 25 and stop rotation of the cam shaft as it enters its first position, while simultaneously 15 returning the movable shearing knife to its original position, thus the parts are ready to receive a second coin and go through the same series of operations. As the lever 25 is oscillated when a coin is in 20 engagement with the members 24^a and 25^a the registering mechanism is operated by such lever.

The article containing strip 100 may be of any approved type, and provided with any 25 approved means for containing the article to be vended, as in this present invention, I make no claim to the specific construction of the strip 100, *per se*, as the same will form 30 the subject-matter of a co-pending application.

While I have not described any particular articles adapted to be sold by this machine, yet the strip 100 may have its pockets 100^a adapted to receive postage stamps which 35 may be sold by the machine, the contents of one pocket being indicated on the front of the machine, and while the machine shown in the drawings is particularly designed and adapted for selling postage stamps, yet it 40 may be easily adapted for selling railway tickets and other vendible articles of merchandise.

From the foregoing description taken in connection with the accompanying drawings, 45 it is thought the complete construction, operation and numerous advantages of my invention will be readily understood by those skilled in the art to which the invention 50 pertains.

50. What I claim is:—

1. In a machine of the class described, a rotatable operating shaft, a feeding mechanism geared with said rotating shaft, a cutting mechanism positively connected with and operable from said operating shaft, said shaft having provisions for alternately operating the feeding and cutting mechanisms, said cutting mechanism comprising a fixed knife, a rock shaft, a movable cutter knife carried by said rock shaft to coöperate with the fixed cutter, connections between said rock shaft and said operating shaft for moving the movable cutter to its various positions, substantially as shown and described.

2. In a machine of the class described, a

rotatable operating shaft, a strip feeding mechanism geared with said rotating shaft, a cutting mechanism positively connected with and operable from said operating shaft, said shaft having provisions for alternately 70 operating the feeding and cutting mechanisms, said cutting mechanism comprising a fixed knife, a rock shaft, a movable cutter knife carried by said rock shaft to coöperate with the fixed cutter, connections between 75 said rock shaft and said operating shaft for moving the movable cutter to its various positions, and a guard coöperating with said drum and said cutter to hold the strip in operative engagement with the feeding mechanism and direct the strip into alinement with the cutting mechanism.

3. In a device of the class described, a rotatable strip feeding mechanism, an operating shaft therefor, a positively actuated cutting mechanism positively connected with said operating shaft to be completely operated thereby, the connections between the strip feeding and cutting mechanisms and the operating shaft having provisions for 90 feeding the strip step by step to the cutting mechanism and positively operating the cutting mechanism after the strip is moved each step.

4. In a machine of the class described, a 95 rotatable feeding drum, a support in which said drum is rotatably mounted, a rotatable operating shaft, gear connections between said operating shaft and said drum, means for preventing rotation of said operating 100 shaft in one direction, a cutting mechanism positively connected with said operating shaft to completely actuate alternately with said drum to cut the strip, means for operating said cutting mechanism from said 105 operating shaft alternately with said feeding drum.

5. In a machine of the class described, a feeding mechanism comprising a rotatable operating shaft, a rotatable drum, gear connections between the operating shaft and the drum for intermittently operating the drum, said drum adapted to feed a continuous envelop, a cutting mechanism for severing said envelop into sections as it is 110 fed by the drum, means positively connected with said operating shaft for intermittently and completely actuating said cutting mechanism from said operating shaft.

6. In a machine of the class described, a 115 vending mechanism comprising a rotatable operating shaft, a rotatable drum, gear connections between the operating shaft and the drum for intermittently operating the drum, said drum adapted to feed a continuous envelop, a cutting mechanism for severing said envelop into sections as it is fed by the drum, means positively connected with said operating shaft for intermittently and completely actuating said cutting mechanism 120

125

130

from said operating shaft, a guard embracing said drum to hold said continuous envelop in engagement with the drum, a supplemental guard coöoperating with said first mentioned guard and held adjacent to said cutting mechanism, said first mentioned guard and said supplemental guard forming a passageway for the continuous envelop from the drum to the cutting mechanism.

10 7. In a vending machine for continuous envelops, a cutting mechanism for severing said envelop into sections, a feeding mechanism for feeding said envelop to said cutting mechanism, a main operating shaft, means positively connected with said operating shaft to completely actuate said cutting mechanism from said main operating shaft, and mutilated gear connections between said main operating shaft and said drum.

15 8. In a vending machine for continuous envelops, a cutting mechanism for severing said envelop into sections, a feeding mechanism for feeding said envelop to said cutting mechanism, a main operating shaft, means positively connected with said operating shaft and completely actuating said cutting mechanism from said main operating shaft, mutilated gear connections between said main operating shaft and said drum, a guard embracing said drum and extending adjacent to said cutting mechanism, a supplemental guard extending between the cutting mechanism and the drum 30 to form a passageway with the first mentioned guard for the continuous envelop from the drum to the cutting mechanism.

35 9. In a vending machine for continuous envelops, a cutting mechanism for severing said envelop into sections, a feeding mechanism for feeding said envelop to said cutting mechanism, a main operating shaft, means positively connected with said operating shaft to completely actuate said cutting mechanism from said main operating shaft, mutilated gear connections between said main operating shaft and said drum, a guard embracing said drum and extending adjacent to said cutting mechanism, a supplemental guard extending between the cutting mechanism and the drum 40 to form a passageway with the first mentioned guard for the continuous envelop from the drum to the cutting mechanism, said drum having peripherally spaced projections to engage apertures in the continuous envelop and said guards having slots to permit passage of said projections.

45 10. In a vending machine for continuous strips, a unidirectionally rotatable operating shaft, a cam member carried by said shaft, a fixed cutter and a pivotally mounted cutter, positive connections between said pivoted cutter and said cam member for completely

50 operating the cutter from the operating shaft, a feeding mechanism comprising a rotatable drum around which a continuous strip is adapted to pass, connections between said operating shaft and said drum for intermittently operating the drum of the feeding mechanism, substantially as shown and described.

55 11. In a vending means for continuous envelops, a unidirectionally rotatable operating shaft, a cam member carried by said shaft, a fixed cutter and a pivotally mounted cutter, connections between said pivoted cutter and said cam member for completely operating the cutter from the operating shaft, a feeding mechanism comprising a rotatable drum shaft around which a continuous strip is adapted to pass, connections between said operating shaft and said drum shaft for intermittently operating the drum shaft of the feeding mechanism, said drum 60 having radial projections, a guard for said drum having a slot to permit passage of said projections, the said guard arranged to guide the strip to the cutting mechanism, substantially as shown and described. 90

65 12. In a vending means for continuous envelops, a unidirectionally rotatable operating shaft, a cam member carried by said shaft, a fixed and a pivotally mounted cutter, connections between said pivoted cutter and said cam member for positively operating the cutter from the operating shaft, a feeding mechanism comprising a rotatable drum shaft around which a continuous strip is adapted to pass, connections between said operating shaft and said drum shaft for intermittently operating the drum shaft of the feeding mechanism, said drum having radial projections, a guard for said drum having a slot to permit passage of said projections, the said guard arranged to guide the strip to the cutting mechanism, and a supplemental guard having scraper portions for engaging the drum to disconnect the strip therefrom and assist the first mentioned guard in feeding it to the cutting mechanism. 100

70 13. In a machine for vending from continuous strips, a rotatable operating shaft, a cam member carried thereby, a fixed cutter and a pivoted cutter, direct connections between the pivoted cutter and the cam member for positively and completely operating said pivoted cutter from the operating shaft, said cam member and said cutter connections including means for locking the cutter during a portion of the rotation of the operating shaft, and a strip feeding mechanism operatively connected with said operating shaft. 115

75 14. In a machine for vending from continuous strips, a rotatable operating shaft, a cam member carried thereby, a fixed cutter and a pivoted cutter, direct connections be- 120

tween the pivoted cutter and the cam member for positively and completely operating said pivoted cutter from the operating shaft, said cam member and said cutter connec-
5 tions including means for locking the cutter during a portion of the rotation of the operating shaft, and a strip feeding mechanism

operatively connected with said operating shaft, and intermittently operatable thereby.
